DEVICE FOR SAMPLING MOLTEN METAL IN
A LADLE OR THE LIKEHoward N. Hubbard and Edward F. Ketterer,
Lorain, Ohio, assignors to National Tube Com-
pany, a corporation of New Jersey

Application March 23, 1948, Serial No. 16,584

10 Claims. (Cl. 73—425.4)

1

This invention relates to a sampling device and, in particular, to a device for taking a sample of molten metal from a deep pool thereof, such as contained in a ladle.

It is desirable for the purpose of analysis and quality-control to take samples of molten metal, e. g., iron or steel, during the manufacturing process. It has been the practice heretofore to take samples from an open-hearth furnace or the iron runner of a blast-furnace by means of a long-handled dipper or "spoon" and pour them into a cast iron chill mold. Samples so taken are satisfactory for chemical analysis but, because they are cooled suddenly, do not reveal the grain characteristics or graphitization to be expected when the metal is cast in a relatively large mass and slowly cooled, i. e., when poured in a large mold such as an ingot mold. In the previous practice, a sample of molten iron, for example, is converted into white chilled cast iron of physical characteristics widely different from those of ordinary gray iron. Micrographic examination of such samples, therefore, gives only limited useful information. Taking samples from the surface also involves an ever-present danger of contamination of the sample by slag floating on the metal.

We have invented a novel device for taking samples whereby the foregoing objections are overcome and a clean, slowly-cooled sample is obtained from which much significant information may be derived by micrographic analysis. The sample thus shows accurately the properties the metal in the main mass will exhibit when cast in molds. In the case of iron, the sample remains normal gray iron instead of being converted to white chilled cast iron. In a preferred embodiment and practice, we place a refractory tube within a shielding sleeve, mount them in one end of a tubular or hollow handle and provide the upper end of the tube with a closure adapted to be burned out on contact with molten metal. A restricted air vent is provided at the bottom of the tube. When the tube is submerged below the surface of the metal, the closure is destroyed, the tube is filled with metal and the air therein is displaced through the vent. The vent is an orifice in a disc of such character as to cause prompt solidification of the metal at the bottom of the tube, thus preventing the tubular handle from being filled with metal. After the tube has been filled, it is removed from the molten metal and the contents cooled slowly. After freezing, the sample is removed from the tube.

We are aware that it has been proposed previously to provide a sample dipper with a temporary closure adapted to be destroyed or fused by the molten metal. Our invention utilizes that expedient but is more particularly concerned with a sampling device insuring slow cooling of

2

the sample whereby the condition of the latter as revealed by micrographic analysis will have significance in respect to the characteristics to be expected of the remainder of the metal when cast.

A complete understanding of the invention may be obtained from the following detailed description and explanation which refer to the accompanying drawing, the single figure of which is a central vertical section through our improved sampling device.

Referring in detail to the drawing, an elongated tubular handle 10, which may be a length of pipe of suitable size, has one end bent to form a crook or U-shaped portion 11 with a relatively short limb. The other end is bent to form a hook 11^a for suspending the sampling device from any suitable support. A bell reducer 12 is threaded onto the upturned lower end of the handle and a sleeve 13 is screwed into the large end thereof. A plate or disc 14 of copper or other metal of high thermal conductivity, having a central orifice 14^a, is seated in the reducer 12 for a purpose which will appear later. A reducer 15 is screwed onto the upper end of sleeve 13.

A refractory tube 16 extends through sleeve 13 and bottoms on disc 14 which forms a closure. Sealing rings 17 of suitable packing material, such as asbestos wick, are applied to the tube 16 and seal the clearance between the tube and the reducers. The tube is preferably inserted in the sleeve and the sealing rings applied before the sleeve is screwed into reducer 12. The tube is composed of heat-resisting glass, quartz, graphite or other suitable material capable of withstanding the temperature of molten iron for a short time at least. It is preferably about $\frac{5}{8}$ " inside diameter and about 9" long, and is provided at its upper end with a temporary closure disc 18 of heat-destructible material, such as pasteboard. The outside diameter of the tube is considerably less than the inside diameter of sleeve 13 whereby an air space 19 is left therebetween.

In using the device described above for sampling, it may first be coated on the exterior with a refractory slurry which, after drying, serves to protect it from the heat of the metal to be sampled. The user then seizes the handle 10 and submerges the lower end in the molten metal to be sampled, e. g., a ladle of iron tapped from a blast-furnace, manipulating the device so that the tube 16 is kept substantially vertical. When the handle has been lowered in the metal to a depth sufficient to cover the upper end of the tube, the closure 18 is burned out and metal flows into the upper end of the tube. As metal descends through the tube, it displaces any air initially trapped therein which escapes through orifice or vent 14^a in disc 14. The metal which first strikes the disc is chilled and quickly solidifies because

of the high thermal conductivity thereof. The disc should be of such mass as to favor this result. A plug of solid metal is thus formed at the bottom of tube 16 which prevents liquid metal from entering the handle 10 through orifice 16a.

When the tube 16 has been filled with molten metal which occurs within a few seconds after destruction of closure 18, the device is removed from the bath and may then be hung up by hook 11a until the sample in the tube has solidified after slow cooling. It will be apparent that the sleeve 13 protects the tube 16 in large part, at least, from direct contact with the air, thus preventing rapid cooling or quenching of the sample. The refractory nature of the tube 16 also delays cooling of the sample. When the sample has cooled substantially to atmospheric temperature, the tube 16 is removed from the sleeve by unscrewing the reducers, and the sample from the tube. Usually the latter requires destruction of the tube but the cost thereof is small. A fresh tube with a closure 18 therein and packing 17 at the ends is inserted in the sleeve and the reducers are coupled to the latter preparatory to the next sampling operation.

The lower end of the sample which is subjected to chilling and quick cooling by contact with disc 14 is cut off and may be discarded or used for chemical analysis. The remainder of the sample, having been slowly cooled, when ground, etched and polished, reveals the grain structure and degree of graphitization to be expected of the main mass of metal if cast in molds for slow-cooling, as well as giving a rating as to any non-metallic inclusions, when examined under the microscope in the known manner. In taking a sample of iron, the sample exhibits the structure characteristic of gray iron and is not converted to white chilled cast iron.

It will be apparent from the foregoing that the invention is characterized by numerous advantages. In the first place, it permits the taking of a clean sample which truly represents the main mass under metallographic as well as chemical analysis. The destructible closure 18 prevents the entry of slag since it is not destroyed until it comes in contact with the molten metal. The slow cooling of the sample resulting from the shielding effect of the sleeve 13 and the refractory coating thereon as well as the air space 19 and the character of the material of which the tube 16 is composed, permits the formation of graphitic carbon and leaves the sample in the form of gray iron except for the initially solidified bottom plug in contact with disc 14. The quantity and distribution of excess carbon may thus be readily observed. The physical examination of a slowly-cooled representative sample should make possible improved operation of the blast furnace and the manufacture of a superior product.

A sample taken by aid of the invention fractures easily for visual examination and is of convenient size for polishing and etching preparatory to metallographic analysis. The replaceable tube 16 produces a smooth-surfaced test piece of uniform diameter. Air initially entrapped in the tube is completely vented, thus preventing the formation of an unsound specimen. Our improved sampling device is well adapted for taking samples from a deep pool, such as a tapping ladle, and it affords a cooling rate which is substantially uniform from sample to sample, regardless of variations in atmospheric conditions.

Although we have illustrated and described but a preferred embodiment and practice of the invention, it will be recognized that changes in the details and arrangement disclosed may be made without departing from the spirit of the invention or the scope of the appended claims.

We claim:

1. A device for taking samples of molten metal comprising a refractory tube, a shielding sleeve surrounding said tube, a handle to which one end of said tube and sleeve are secured, said handle having an exit passage for air displaced from said tube, and a disc at said one end of said tube having an air vent therein.
2. In a device for sampling molten metal, an elongated member adapted to have one end immersed in the metal, a refractory tube extending upwardly from said one end of said member, said member having a passage for air displaced from said tube, and a closure at the lower end of the tube having an air vent therein.
3. The apparatus defined by claim 2 characterized by a shielding sleeve surrounding said tube.
4. In a device for sampling molten metal, an elongated handle, a sampling tube fixed at one end of said handle and extending upwardly therefrom, said handle having an exit passage for air displaced from said tube, and a disc at the lower end of said tube having an air vent therein.
5. The apparatus defined by claim 4 characterized by a shielding sleeve surrounding said tube.
6. The apparatus defined by claim 4 characterized by said handle being tubular.
7. In a device for sampling molten metal, a U-tube, one limb of which is shorter than the other, a sampling tube fixed in and extending upwardly from said shorter limb, and an orifice plate at the bottom of said sampling tube permitting the escape of air but restricting flow of metal from the sampling tube to the U-tube.
8. The apparatus defined by claim 7 characterized by a shielding sleeve surrounding said sampling tube.
9. A device for sampling molten metal comprising a tubular handle, a shielding sleeve secured to one end of said handle and extending upwardly therefrom, a sampling tube disposed within said sleeve, and an orifice plate at the bottom of the sampling tube.
10. The apparatus defined by claim 9 characterized by said handle having a crook at said one end.
